Inventor:

F. HOOPER

or Father & Son
ATTYS.

UNITED STATES PATENT OFFICE.

FOREST HOOPER, OF EDMONTON, ALBERTA, CANADA.

CONNECTION BETWEEN VEHICLE POLES AND YOKES.

1,360,528.

Specification of Letters Patent. Patented Nov. 30, 1920.

Application filed December 27, 1919. Serial No. 347,649.

To all whom it may concern:

Be it known that I, FOREST HOOPER, of the city of Edmonton, in the Province of Alberta, Canada, have invented certain new and useful Improvements in Connections Between Vehicle Poles and Yokes, of which the following is the specification.

My invention relates to improvements in connections between vehicle poles and yokes, and the object of the invention is to devise a simple and effective connection whereby a yoke can be connected to the tip of the pole and retained thereon when the yoke is in the more or less horizontal position and which will be released when the yoke is turned into the vertical position.

My invention consists of a sleeve adapted to be secured about the yoke intermediately of its length and provided with a hollow boss having a cross slot in the outer face thereof, and a T-shaped member secured to the tip of the pole, all as hereinafter more particularly described, and illustrated in the accompanying drawing, in which:—

25 Figure 1, represents a perspective view of a connection constructed according to my invention, showing the same applied to the pole and yoke.

Fig. 2, is an enlarged elevation of the tip 30 of the pole, showing the connection in section.

Fig. 3, is an enlarged plan view of the tip 35 of the pole, showing the yoke and connection in section, the former turned in the vertical position and about to be disengaged from the pole.

Like characters of reference indicate corresponding parts in the different views.

1 is the pole and 2 is the yoke provided 40 with the sleeve 3 extending about the same intermediately of its length. 4 is the hollow boss provided with a cross slot 5 extending through the outer face thereof. 6 is a suitable member having extending portions 7 45 adapted to be secured to the pole and having a neck 8 at its forward end carrying the cross bar 9, the said member 6 forming with the neck 8 and the cross bar 9 the T-shaped member.

The device is applied as follows:—The 50 member 6 is attached to the tip of the pole 1 in such a position that the cross bar 9 will be vertical. When it is desired to apply the yoke to the pole the yoke is turned in the vertical position and the cross bar 9 inserted 55 into the slot 5 in the outer face of the boss 4. The yoke is then turned into the horizontal position when the cross bar 9 will engage the interior of the forward face of the hollow boss 4, thus preventing the device becoming disconnected. 60

It will be seen that the yoke is free to swing in practically any position other than vertical without becoming disengaged and consequently will constitute a reliable and 65 effective connection and yet give the maximum of freedom to the horses.

What I claim as my invention is.

1. In combination with a vehicle pole and yoke, a sleeve surrounding the intermediate 70 portion of the yoke and carrying on one side a hollow casing, said casing comprising an outer wall spaced from the body of the sleeve and having a cross slot formed therein, and side walls extending between 75 said outer wall and the sleeve, and a coupling member carried by the pole and presenting a shank provided with a cylindrical cross head tapering toward its ends and adapted to be inserted through the slot in 80 said casing to couple the yoke and pole together.

2. The combination with a vehicle pole and yoke of a sleeve received on the yoke and carrying an integral slotted wall or 85 plate supported in spaced relation to the body of the sleeve and upon one side thereof, to provide an intervening space, and a coupling head adapted to be received in the slot of said sleeve when the yoke is disposed 90 vertically with respect to the pole and to engage the rear wall of said plate when the yoke is disposed horizontally with respect to the pole, thus coupling the yoke and pole together in the operative position of the 95 former.

FOREST HOOPER.
